UNITED STATES PATENT OFFICE.

JULIUS KINDERVATER, OF NEW YORK, N.Y.

STEAM BOILER.

Application filed June 14, 1923. Serial No. 645,294.

To all whom it may concern:

Be it known that I, JULIUS KINDERVATER, a citizen of the United States, and a resident of New York, in the county and State of New York, have invented a certain new and useful Improvement in Steam Boilers, of which improvement the following is a specification.

My invention relates to steam boilers of the locomotive type, and its object is to provide a boiler of such type which shall embody the advantages of affording free circulation of water, strength of general structure, ready access to tubes, and ample steam storage capacity.

The improvement claimed is hereinafter fully set forth.

In the accompanying drawings: Figure 1 is a view, partly in side elevation and partly in vertical longitudinal section, on the line *a a* of Fig. 2, of a steam boiler illustrating an embodiment of my invention; Figs. 2 and 3, vertical transverse sections through the same, on the lines *b b* and *c c*, respectively, of Fig. 1; Fig. 4, a partial horizontal axial section, on an enlarged scale, through one of the end portions of a water tube; Fig. 5, a partial similar section, on a further enlarged scale, showing the manner of closing the tube ends; and, Fig. 6, a transverse section through a water tube, on the line *d d* of Fig. 4.

In the practice of my invention, referring descriptively to the specific embodiment thereof which is herein exemplified, the firebox is preferably, as shown, of rectangular horizontal section, increasing in width from top to bottom to permit of the application of any desired extent of grate area, and comprises a front header or water leg, 1; a back header or water leg, 1^a; a plurality of water tubes, 2, connecting said headers; two bottom water drums, 3, 3, located on opposite sides of the firebox, and connecting the headers, adjacent to their bottoms; and a casing, 4, of material of low heat conducting capacity, as magnesia, asbestos, mineral wool, etc., which closes the top and sides of the firebox. One or more door openings, 1^c, closed by suitable doors, are formed in the back header, and stay bolts are secured, in the usual manner, in the portions of both headers which are not stayed by the water tubes and bottom drums. Arch tubes, 5, are beaded into place on the inner sheet of the front header, 1, and extending upwardly

and rearwardly therefrom, communicate, at their tops, with members of the system of water tubes, 2, to which they are welded. Baffle bricks, 5^a, are laid upon the arch tubes, 5, to rearwardly diverge the heated gases from the combustion of the fuel on the grate, which is not shown, but may be of any suitable and preferred known construction.

As shown in Fig. 1, the front header, 1, is of greater depth than the rear header, 1^a, and the two outer rows of water tubes, 2, on each side of the firebox, which constitute side walls thereof, are correspondingly downwardly and forwardly inclined, the intermediate members of the set of water tubes being oppositely inclined.

A horizontal steam drum, 6, is located at the top of the firebox, communicating, through openings in its bottom, with the back and front headers, and is reduced in diameter in front of the latter, from which it extends to a cylindrical steam delivery chamber, 7, which forms the rear portion of the waist of the boiler, and is adapted to receive a throttle valve box or casing, 8, the ordinary steam dome being dispensed with. The steam delivery chamber, 7, is connected with the smoke box, 9, by a waist section, 10, which is of smaller diameter, and of conical form, tapering inwardly from the chamber, 7, to the smoke box, and containing a plurality of smoke tubes, 11, leading from the front of a combustion chamber, 12, to the smoke box.

The waist section, 10, is connected by an upwardly extending channel, 10^a, with a supplemental steam drum, 6^a, which extends from the steam delivery chamber 7 to the back sheet of the smoke box, and encloses a dry pipe, 8^a, through which steam may be supplied to a superheater header, 8^b, in the smoke box 9, or directly to the cylinders of the engine, as preferred. The location of the throttle box does not form part of my present invention, and it may, without departing therefrom, be interposed between the superheater header and the engine cylinders, as in instances of present practice, steam being, in such case, delivered directly from the chamber 7, to the dry pipe.

Communication between the interior of the firebox and the discharge smoke tubes, 11, is established through a combustion chamber, 12, the rear portion of which is in the form of a corrugated tube, enclosed in a water casing, 13, communicating, at

its ends, with the water spaces of the front header, 1, and of the steam delivery chamber, 7. The casing, 13, is of such comparatively small diameter as not to interfere with free access to the ends of the water tubes, 2, for application or repair. The forward portion of the combustion chamber, 12, which is located in the steam delivery chamber 7, is enlarged in diameter sufficiently to receive the set of smoke tubes, 11, which are expanded into its front sheet. The relation of the ends of the water tubes, 2, to the headers, 1, 1^a, and the manner of closing the tube ends, are clearly shown in Figs. 4 to 6 inclusive. The tubes communicate with the water spaces of the headers, through slots, 2^a, cut in the tubes, and the tube ends are closed by plugs, 2^b, which are drawn to a tight bearing in copper washers, 2^c, interposed between their inner ends and bevelled surfaces on the ends of the tubes, by nuts, 2^d, engaging screw threads, 2^e, on the plugs, and bearing on cap rings, 2^f, enclosing the ends of the tubes. The tubes are first prepared by bevelling their ends, on their inner and outer surfaces, expanding them into the sheets of the headers, and further securing them by welding to the outer sheets, and inserting the washers, 2^c, as shown in Fig. 5. The washers are then expanded, and a tight joint formed, by drawing the plug outwardly by the nuts, 2^d.

It will be seen that, in a steam boiler of the construction substantially as hereinbefore set forth, the application of water tubes in lieu of water legs in the formation of the sides of the firebox, and the interposition between the sides of the firebox, of a plurality of water tubes, materially promotes the free circulation of water, and likewise substantially increases the area of firebox heating surface. The ends of the water tubes are, at all times, perfectly accessible, and the elimination of the usual stay bolts in the sides of the firebox is a feature of much importance, both as to increasing safety and reducing cost of construction and maintenance. The reduction of diameter of the major portion of the waist of the boiler, promotes its strength without objectionable reduction of the area for the traverse of products of combustion

from the firebox to the smoke box and stack.

I claim as my invention and desire to secure by Letters Patent:

1. In a steam boiler of the locomotive type, the combination of a front and a back firebox header or water leg; a plurality of inclined water tubes, connecting said headers, and constituting the side walls of the firebox; a plurality of reversely inclined water tubes, interposed between the side wall tubes and connecting said headers; arch tubes leading from the front header into members of the intermediate set of water tubes; a steam drum, communicating with the headers, above the water tubes; and a combustion chamber, communicating with the firebox.

2. In a steam boiler of the locomotive type, the combination of a firebox, comprising front and back headers or water legs, and connecting water tubes; a cylindrical steam delivery chamber, located forward of the firebox; a water casing, of smaller diameter, connecting the front header and the steam delivery chamber; a combustion chamber, extending through the front header and the water casing, into the steam delivery chamber; a smoke box; a waist section of conical form and smaller diameter, extending from the steam delivery chamber to the smoke box; smoke tubes, extending through said section, from the combustion chamber to the smoke box; and steam drums, communicating with the firebox headers, the steam delivery chamber and the waist section.

3. In a steam boiler of the locomotive type, the combination of a firebox; a cylindrical steam delivery chamber located forward thereof; a water casing, of smaller diameter, connecting the front water space of the firebox with said chamber; a conical waist section, also of smaller diameter, connected to said chamber; steam drums located above the firebox and waist section, and communicating therewith and with the waist section; a smoke box; a combustion chamber and smoke tubes establishing communication between said combustion chamber and smoke box.

JULIUS KINDERVATER.
